UNITED STATES PATENT OFFICE.

RAYMOND E. MEYER, OF SYRACUSE, NEW YORK.

SPARK PLUG.

Application filed October 8, 1920. Serial No. 415,619.

To all whom it may concern:

Be it known that I, RAYMOND E. MEYER, of Syracuse, in the county of Onondaga, in the State of New York, have invented new and useful Improvements in Spark Plugs, of which the following, taken in connection with the accompanying drawings, is a full, clear, and exact description.

This invention relates to certain improvements in spark plugs as used more particularly for ignition purposes in internal combustion engines.

The main object is to increase the strength, durability and working efficiency and, at the same time, reduce the liability of short circuiting due to accumulations of carbon at the joints between the insulator and its support.

One of the specific objects is to seat the ends of the insulating sleeve in annular grooves in the clamping head and collar to prevent expansion or mutilation thereof when tightening and releasing the insulator disks upon and from the support.

Another specific object is to enable the laminated disks to be adjusted along and upon the sleeve and to be compressed more firmly by the clamping head and collar to increase the degree of insulation, if necessary.

Other objects and uses relating to specific parts of the spark plug will be brought out in the following description.

In the drawings:

Figures 1 and 2 are vertical sectional views of modified forms of my invention.

Figure 3 shows perspective views of the detached insulator sleeve and insulator disks.

Figure 4 is a perspective view of the detached conductor having a clamping head and one of the spark terminals shown in Fig. 1.

Figures 5, 6 and 7 are transverse sectional views taken respectively on lines X-X, Fig. 1, Y-Y, Fig. 2, 2 and Z-Z, Fig. 1.

Figure 8 is a perspective view of the lengthwise conductor having the clamping head and spark terminal shown in Figure 2.

In Figure 1, I have shown a spark plug consisting of an insulator support —1— having a central lengthwise bore —2— for receiving an insulating sleeve —3— which is extended through and beyond the opposite ends of the bore for receiving a pair of insulator disks —4— and —5—.

The support —1— comprises a main body —6— and a bushing —7—, the main body being provided with a reduced externally threaded inner end —8— adapted to be screwed into an internally threaded opening —9— of an internal combustion engine —10— and forming a shoulder —11— for engaging a packing —12— and preventing leakage of the gases at the joint.

The bushing or follower —7— is screwed tightly into the outer end of the section —6— and against a suitable packing —12'— to prevent leakage at the joint, the inner end of said bushing being of considerably less diameter than the interior diameter of the larger part of the section —6—, and of substantially the same diameter as that of the inner disk —4— to form a chamber —13— extending upwardly beyond the lower end face of the reduced portion, as —14—, so that any carbon which may tend to accumulate in the chamber will impinge against the upper end wall, as —15— of said chamber some distance above the insulator —4—, where the tendency to short circuit between the lamina of the insulator will be reduced to a minimum.

An electric conducting spindle —16— extends through and beyond the opposite ends of the insulator sleeve —3— and is provided at its inner end with a head —17— having an annular groove —18— for receiving the inner or adjacent end of the sleeve, said head being engaged with the inner face of the disk —4— to clamp the same firmly against the reduced inner end of the bushing —7—.

This head —17— is provided with a reduced extension —19— forming a spark terminal which projects inwardly beyond the inner end of the reduced portion —8— of the section —6— to cooperate with a companion spark terminal —19'— on the inner end of the section —6— for igniting the explosive mixture of the engine when energized.

A collar —20— loosely surrounds the outer end of the spindle —16— and is engaged with the outer face of the outer insulator disk —5— to firmly clamp the same against the outer face of the support —1—, or rather bushing —7—, said spindle having its outer end threaded and engaged by one or more nuts —21— for tightening and releasing the collar upon and from the disk, and also for establishing an electrical con-

nection with a suitable conductor —22— with one side of the ignition circuit, the other side of said circuit being grounded on the frame of the engine which is in electrical connection with the terminal —19—. The laminated sleeve —3— is preferably made of layers of mica wrapped or rolled one upon the other to form a sufficient thickness of insulation to prevent any possibility of short circuit between the conductor —16— and support —1—.

The laminated disks —4— and —5— are also made up of layers of mica firmly clamped together by the head —17— and collar —20—, which are relatively adjustable endwise by means of the nuts —21— to compress the disks firmly against the adjacent ends of the bushing —7—.

In Figure 2, the insulator support is preferably made in one piece consisting of a bushing —7'— having a lengthwise bore —2'— which, however, is eccentric to the axis of the bushing, this, in order that the conducting spindle, as —16'— may be offset a sufficient distance to one side of said axis to permit the use of a straight upright terminal —23— on the inner end of the bushing a sufficient distance from the head, as —17'—, of the conductor to reduce the possibility of short circuits between said terminal and conductor.

The inner end as —14'— of the bushing —7'— is reduced in diameter concentric with the axis of the bore —2'— and forms a shoulder —15'— some distance above the end face of the reduced portion —14'— to keep the carbon which may tend to deposit thereon away from the inner insulator disk as —4—. The head —17'— like the head —17— is secured to the conductor —16— and is provided with an annular groove —18— in its upper face for receiving the adjacent end of the insulator sleeve —3—, said head being also provided with a radially projecting terminal —24— to cooper-

ate with the terminal —23— for producing the necessary ignition spark.

Aside from the differences pointed out, the construction of the spark plug shown in Fig. 2 is similar to that shown in Figure 1.

What I claim is:

A spark plug comprising a bushing having a lengthwise bore mainly at one side of its axis, said bushing having a reduced inner end concentric with the bore, a spark terminal secured to and projecting inwardly from the inner end of the bushing at the opposite side of said axis and in spaced relation to the reduced extension, an insulator sleeve extending through the bore, a conductor extending through the sleeve, a head secured to the inner end of the conductor and provided with a spark terminal cooperating with the first named terminal, for ignition purposes, said head having an annular groove for receiving the inner end of the sleeve, an insulator disk adjustable lengthwise of and upon the inner end of the sleeve between the head and reduced end of the bushing, a collar loosely surrounding the outer end of the conductor and provided with an annular groove for receiving the outer end of the sleeve, an insulator disk adjustable lengthwise of and upon the outer end of the sleeve between said collar and outer end of the bushing, and means for adjusting the collar and conductor axially relatively to each other for tightening the disks in place, one of said grooves being of sufficient axial depth to allow its end wall to clear the adjacent end of the sleeve when the disks are tightened against the adjacent ends of the bushing.

In witness whereof I have hereunto set my hand this 1st day of October, 1920.

RAYMOND E. MEYER.

Witnesses:

H. E. CHASE,
ROSE G. CARROLL.
